W. H. MUZZY,
FUEL FEEDING SYSTEM FOR AUTOMOBILES,
APPLICATION FILED MAY 26, 1917.

1,294,521.

Patented Feb. 18, 1919.

UNITED STATES PATENT OFFICE.

WILLIAM H. MUZZY, OF DETROIT, MICHIGAN.

FUEL-FEEDING SYSTEM FOR AUTOMOBILES.

1,294,521.

Specification of Letters Patent. Patented Feb. 18, 1919.

Application filed May 26, 1917. Serial No. 171,180.

To all whom it may concern:

Be it known that I, WILLIAM H. MUZZY, a citizen of the United States, residing at Detroit, in the county of Wayne and State of Michigan, have invented certain new and useful Improvements in Fuel-Feeding Systems for Automobiles, of which I declare the following to be a full, clear, and exact description.

10 This invention relates to improvements in fuel feeding systems for automobiles or the like and has more particular relation to improvements in devices of the character shown and described in my patents numbered 1,201,077, issued Oct. 10, 1916, and 1,222,235, issued Apr. 10, 1917, and my co-pending application No. 151,023, filed Feb. 26, 1917.

One of the several objects of the invention is to provide improved means whereby in a vacuum system such as shown in my aforesaid patents there will be no chance of the system becoming exhausted by all of the gasoline passing out of the same.

25 Another object is the provision of means for causing a positive operation of the siphon.

Another object of the invention is the provision of improved means for suspending 30 the operation of the devices when the tank has taken its maximum quantity.

35 A further object of the invention is the provision of means for preventing the gasoline from passing into the air suction pipe when the tank is tipped abnormally by the car going down a very steep grade.

40 A still further object of the invention is the provision of a simplified construction of siphon and air feed pipe and the control devices connected thereto.

In carrying these and other objects of the invention into effect I utilize certain constructions, combinations and arrangements of parts all of which will be hereinafter 45 more particularly set forth and claimed.

In the accompanying drawings forming part of this specification;

Figure 1 represents a central vertical section through a vacuum fuel feeding tank embodying my invention, and

Fig. 2 represents a detail front elevation of one of the gravity valves.

In general terms the invention may be said to operate by the suction from the manifold of the engine and draw the gasoline from a relatively low main fuel tank at the

rear of the car in intermittent pumping operations as described and shown in my aforesaid patents and application and reference is made to the patents for any further description of these parts desired. After being drawn into the elevated tank the gasoline is fed to the relatively lower carburetor of the engine by gravity. This is all old and well known in the art.

In the aforesaid drawings 1 represents the outer chamber or tank, 2 the vacuum chamber or tank and 3 the intermediate control chamber. The gasoline is drawn from the main supply tank at the rear of the car 60 and fed into the vacuum chamber or tank 2 through a pipe 13 suitably mounted in the top plate 35 to which latter the tanks 2 and 1 are secured by flanges 37 and 38 and screws 36 with suitable intermediate packing. The 65 gasoline discharges from the tank 2 through pipes 10 and 11 each of which is provided at its lower end with a one way gravity valve of a well known type. This valve 70 comprises in each instance an apertured seat 24 and a flapper valve 22 covering the aperture therein. This flapper normally seats by gravity and is held in position by two screws 23 which pass through enlarged apertures formed in the flapper and screw into 75 the seat 24. The heads of the screws limit the outward movements of the flapper. The 80 valve connected to the pipe 11 is detachable by means of screw threads 26 so that the pipe 11 may be passed through the compression attachment 31 fast in the bottom of the tank 3 when the devices are assembled, and the seat 24 then applied. The flapper 85 of this valve is also formed with a small notch 30 so that enough gasoline may escape past the valve to fill the pipe 11 during the pumping operation and thus prevent air from being trapped in the pipe.

It will be seen from the above that the tank 3 which is in the form of a deep cup is supported in position by the pipe 11, and the compression attachment 31. The cup extends up about the tank 2 as shown so that no more than the desired quantity may ever collect in the cup. The quantity of gasoline 90 in this cup determines the duration of the pumping cycle and can be increased or decreased by changing the size of the siphon cap 6 to meet different conditions for different engines. The pipe 11 is soldered 95 fast in the bottom of the tank 2 and projects up into the same a sufficient distance

to assure that the proper quantity of gasoline will always be trapped in the tank 2 to fully supply the tank 3 and not get into the outer tank 1 where it would be lost 5 as far as the tank 3 is concerned.

The siphon comprises a cap 6 and a tube 5, the latter soldered fast in the bottom of the cup 3 and the former soldered fast to the air control pipe 4, this pipe in turn being soldered fast in the bottom of the tank 2. The pipe 4 extends from near the top plate 35 to a slight distance below the bottom of the tank 3. The lower end of the pipe 5 is closed and connected to the level control 10 pipe 7. This pipe is bent and projects upward to near the upper end of the tank 3 and near its upper end is formed with air apertures 9. A cap pipe 8 having its upper end closed is placed over the pipe 7 and 15 extends with its lower open end to a level near the bottom of the tank 3. This level is the control level of the gasoline in the tank 1.

It will be seen that the valves 22 are always covered with gasoline and thus effectively sealed against the passage of air so that they are always ready to pump. The lower end of the cap 6 is so located as to maintain the level *a*—*a* while the carburetor 20 supply pipe 25 projects far enough into the tank 1 to maintain the level *c*—*c*. The level *b*—*b* is the working level maintained by the control tube 8.

The suction pipe 12 from the manifold of the engine is connected to the top plate 35 in any suitable manner, said plate being also formed with a cleaning aperture closed by a plug 33.

In devices such as herein described, when 40 the car is going down a grade so steep that the tank at the rear of the car takes a position higher than the tank 1 the gasoline in the rear tank will feed by gravity into the tank 2 and would pass into the pipe 12 unless means is provided to prevent this. This 45 means in the present case is a cork float 14 supported by a pivoted arm 16. The float is provided with a pin 21 having an enlarged head to which is pivoted the stem 19 of the conical valve 15. The stem is provided with a laterally projecting pin 20 which rests in enlarged horizontal apertures 34 of the lever 16; the latter being formed with a vertical aperture 40 shown in dotted 50 lines and through which the stem 19 passes. Should the tank 2 flood as above described the valve 15 will rise and close the end of the pipe 13 and prevent the gasoline from filling the chamber. The cycles of pumping will 55 continue however without any gasoline being fed from the main tank until the supply in the chamber 2 is lowered enough to allow the valve 15 to again uncover the pipe 13.

When the engine of the car is stopped all 60 the gasoline in the tank 2 will be free of

the suction and will descend by gravity into the tanks 1 and 3. This will leave the tank 3 filled and ready for operation and the siphon filled with the pipes 4 and 7 obstructed. When the engine is started the suction in 70 the tank 2 will draw the gasoline up the pipe 4 which is of small diameter and at the same time through the pipe 13 from the main tank. Finally the gasoline from the tank 3 will be exhausted and air will pass 75 up the pipe 4 and allow the gasoline in the tank 2 to descend through the pipes 10 and 11. When the gasoline in the tank 3 reaches the upper end of the pipe 5 it flows down this pipe and covers the ends of the pipes 80 4 and 7 and starts the pumping operation again. When the gasoline in the tank 3 reaches the lower end of the cap pipe 6 the siphon is broken and air passes up the pipe 4 and the operation is repeated, the pipe 7 85 clearing of gasoline as the siphon clears. When the gasoline lets down through the pipe 11 and rises in the tank 1 until it seals the lower end of the cap pipe 8, the gasoline is drawn up in the pipe 8 a certain distance by the suction through the pipe 7 and 90 apertures 9 but not far enough to pass into the pipe 7. It will be remembered that this operation takes place while the gasoline is starting to fill the tank 3 and therefore just 95 as soon as the lower end of the pipe 8 is sealed and the air to the pipe 4 cut off the suction from this latter pipe will cause the siphon to operate even though the gasoline has not reached the upper end of the pipe 5. 100 When the siphon empties, it now stays empty as the air tube 7 is sealed and gasoline can only pass down into the tank 3 until it seals the lower end of the pipe 6 when gasoline will start to pass through the 105 siphon and pipe 4 together with air. This does not close the pipe 4 sufficiently to cause any pumping operation and the operation of the tank is suspended until the gasoline in the tank 1 has again uncovered the lower 110 end of the pipe 8 when air can again pass through the pipe 7 and allow the tank 3 to fill and the pumping operations to be resumed. It will be observed that the level 115 *b*—*b* is below the valve connected to the pipe 10 and the feed through the pipe 11 always dominates the feed through the pipe 10. Thus when the suspended operation above described is taking place, the gasoline in the tank 2 above the upper end of the pipe 11 will gradually pass down the pipe 11 and into the tank 1 keeping the lower end of the pipe 8 sealed until the level in the tank 2 descends below the upper 120 end of the pipe 11. When the level in the tank 1 lowers and uncovers the lower end of the pipe 8, the gasoline that has been partly drawn up into this pipe will pass back into the tank 1 and leave pipe 8 free for the passage of air. As the distance gas- 130

- olene would have to be raised in the pipe 8 before it could flow into pipe 7, is greater than the greatest elevation it would have to rise to flow through the siphon 5-6 the 5 siphon always operates rather than the gasolene to pass up far enough in the pipe 8 to enter the pipe 7 through port 9.
- It will be understood that in the normal 10 operation of the tank the float does not come into operation at all but I do not care to be limited in this respect as the float may very well operate at all times to shut off the feed of gasolene when the tank 2 becomes too full and in such case the control pipe 8 may be 15 eliminated if desired. In most machines the grade at which the gasolene from the main tank would flow by gravity into the vacuum tank is about 15% and roads of this grade are not often encountered.
- 20 It will be seen from the above that should the tank 1, over night, become exhausted, by a leaky carburetor for instance, that the lower valve 22 still remains covered and the devices ready to operate when the engine is 25 started.

Further the devices will operate and go through their cycles of operation even though only a few drops are pumped each time and these few drops are fed to the 30 tank 1.

A cleaning plug 32 is provided in the bottom of the tank 1.

It will further be observed that when the tank 3 fills and the gasolene starts to run 35 over or splash over the top of the tube 5, this gasolene will pass down the tube and will seal the air pipe 7 through which air is passing to the tube or vent 4 and will thus cause the suction to be exerted on the 40 siphon to draw the gasolene over the top of the tube 5 in volume and thus cause a full and perfect operation of the siphon which will in turn cause the sealing for a predetermined time of the pipe 4 and a corresponding pumping operation of the same 45 duration. The peculiar construction of the siphon also causes the suction through the pipe 4 to fully clear the siphon when the latter breaks after a full operation. A small 50 siphon when it breaks is apt to retain a small amount of the liquid in each end held in suspension. This would interfere with the next operation of the siphon. The liquid in the lower part of the pipe 7 is not elevated, however, until after the siphon fully 55 clears because of the suction from the pipe 4.

Having thus described my invention what I claim as new and desire to secure by Letters Patent is:

- 60 1. In a fuel feeding system the combination with an elevated tank having a vacuum chamber and a supply chamber, of a vacuum pipe connected to the vacuum chamber, a fuel supply connection for the vacuum chamber, a control tank, an air pipe for the

vacuum chamber and means for sealing and unsealing the air pipe from both the control tank and the supply chamber.

2. In a fuel feeding system the combination with an elevated tank having a vacuum 70 chamber and a supply chamber, of a vacuum pipe connected to the vacuum chamber, a fuel supply connection for the vacuum chamber, a control tank, an air pipe for the vacuum chamber sealed and unsealed by the 75 gasolene in the control tank and a pipe sealed and unsealed by the gasolene in the supply chamber and connected to supply air to the air pipe when the connection of the latter with the control tank is sealed. 80

3. In a fuel feeding system the combination with an elevated tank having a vacuum chamber and a supply chamber, of a control tank, a vacuum pipe connected to the vacuum chamber, a fuel supply connection 85 for the vacuum chamber, a siphon controlling the discharge from said control tank, an air pipe for the vacuum chamber receiving the supply from the siphon and an air pipe connected to the siphon and controlled 90 from the supply chamber.

4. In a fuel feeding system the combination with an elevated tank having a vacuum chamber and a supply chamber, of a vacuum pipe connected to the vacuum chamber, a fuel supply connection for the vacuum chamber, an air vent for the vacuum chamber, means including a siphon for sealing and unsealing the air vent and devices for compelling a full flow of the siphon when a 100 partial flow is started.

5. In a fuel feeding system the combination with an elevated tank having a vacuum chamber and a supply chamber, of a vacuum pipe connected to the vacuum chamber, a fuel supply connection for the vacuum chamber, an air vent for the vacuum chamber sealed and unsealed by the liquid gasolene to cause pumping cycles, a valve for closing the fuel supply, and means for operating the 105 valve when the maximum capacity of the tank is reached. 110

6. In a fuel feeding system the combination with an elevated tank having a vacuum chamber and a supply chamber, of a vacuum pipe connected to the vacuum chamber, a fuel supply connection for the vacuum chamber, a control tank, independent connections from the vacuum chamber to the control tank and to the supply chamber, an air vent 115 for the vacuum chamber and a siphon in the control tank arranged to receive the lower end of the air vent. 120

7. In a fuel feeding system the combination with an elevated tank having a vacuum chamber and a supply chamber, of a vacuum pipe connected to the vacuum chamber, a fuel supply connection for the vacuum chamber, a control tank receiving its supply from 125 the vacuum chamber, a siphon in the control 130

tank, an air vent for the vacuum chamber sealed and unsealed by the siphon, and means controlled by the gasoline in the supply chamber for sealing and unsealing the siphon independently of the gasoline in the control tank.

8. In a fuel feeding system the combination with an elevated tank having a vacuum chamber and a supply chamber, of a vacuum 10 pipe connected to the vacuum chamber, a fuel supply connection for the vacuum chamber, a control tank receiving its supply from the vacuum chamber, means connecting the vacuum and supply chambers inde-

pendently of the control tank, an air vent 15 for the vacuum chamber, a siphon in the control tank arranged to seal and unseal the air vent and controlling means for holding the level of gasoline in the supply chamber below the operating level in the control tank 20 to cause the feed to the supply chamber to dominate.

In testimony whereof I affix my signature in the presence of two witnesses.

WILLIAM H. MUZZY.
